UNITED STATES PATENT OFFICE.

WILLIAM BREITENSTEIN, OF NEW YORK, N. Y.

IMPROVEMENT IN POWER-LOOMS FOR WEAVING CONCAVE AND CONVEX SURFACES.

Specification forming part of Letters Patent No. 58,589, dated October 9, 1866.

To all whom it may concern:

Be it known that I, WILLIAM BREITENSTEIN, of the city, county, and State of New York, have invented certain new and useful Improvements in Power-Looms for Weaving Cloth with Concave and Convex Surfaces, suitable for making corsets and other articles; and I do hereby declare that the following is a full, clear, and exact description thereof, reference being had to the accompanying drawings, making part of this specification, in which—

Figure 1 is a side elevation, and Fig. 2 a front elevation, of the entire loom; Fig. 3, a rear view of the take-up mechanism, and Fig. Fig. 4 a side elevation of the same; Fig. 4^a, a cross-section of the take-up on an enlarged scale; Fig. 5, a front view of the lay and shuttle mechanism; and Fig. 6, a section of the lay and shuttle mechanism, and side view of the cams and connections for operating the shuttle mechanism; Fig. 7, a front view, and Fig. 8 a side view, of the thread-puller and mechanism for operating it.

The same letters indicate like parts in all the figures.

The weaving of cloth suitable for making corsets to fit the swells and protuberances of the body has been attended with serious difficulties. It has been effected in hand-loom, but at considerable expense on account of the great amount and cost of labor.

The required shapes can only be given in weaving by making the cloth of different lengths in different parts of the widths. Whenever a gore-like swell is required, it is produced by interweaving the warps and weft in such parts of the width and suspending the interweaving in the other parts of the width.

The suspension of the interweaving operation in certain portions of the width and along desired portions of the length of the cloth is effected by suspending the operation of the mail-cords of the jacquard, so that the weft-thread cannot pass between the warps in the parts so suspended while it continues to be passed between the warps where the mail-cords continue to open the shed of the warps; and as the interweaving is required to vary from small portions of the width to the whole width, and sometimes to take place near one selvage and at other times toward the oppo-

site selvage, the shuttle-thread is required to be carried across the whole width at each operation.

In weaving such like forms by hand the cloth, as woven, is taken up by the weaver in the portions of the width in which the interweaving has taken place, and when the interweaving takes place in less than the whole width, the weaver is required at each operation to pull by hand the surplus weft-thread, or else such surplus weft-thread would be left projecting from the surface of the cloth.

My said invention relates to machinery for performing all of the said operations automatically. The Jacquard machinery, as heretofore, is employed to determine, during the progress of the weaving and at each operation, what portion of the width of the warp is and what portion is not to be operated.

A mechanism termed the "sectional take-up," and operated by the loom, takes up the cloth as it is woven either along the whole or any portion of the width, and what portion of this mechanism is to be put in action at each operation is determined by the jacquard; and a mechanism operated automatically by the loom pulls out to the required extent the surplus of the shuttle-thread whenever the interweaving is performed on less than the whole width of the cloth, and whenever the interweaving is extended across the whole width the operation of this mechanism is suspended by the jacquard.

In the accompanying drawings, *a* represents the lay, which receives motion, in the usual manner, from cranks at each end of the main shaft *b*. The lay is suspended and has its axis of vibration above, as a matter of convenience, to afford more room below for other parts of the mechanism.

The Jacquard machinery, of the usual construction, is represented at *A*. It derives motion from a crank, *B*, on the main shaft by a connecting-rod, *C*, in the usual manner.

The warp *c* is divided into equal sections, the number being determined by the judgment of the constructor. The drawings represent it as divided in twenty sections. Each section is wound upon a separate spool, *d*, and all the spools are mounted on a creel or frame, *e*, at the back of the loom. From the spools each section passes up over a roller, *f*, down under

a roller on a tension-weight, g , up again over another roller, and down around a warp-beam, h , in the rear part of the frame. All the warps extend from the beam h through the mails of the jacquard-cords, and then through the reed to the sectional take-up in front. In this way each section of the warp can be supplied independently of the others, while all are under equal tension.

The take-up D is attached to the inner face of the breast-beam of the frame, and should have as many sections as the warps, twenty being represented in the drawings. There are twenty (more or less) fluted rollers, j , all of equal diameter and length, and all mounted side by side on a journal-bar, k , secured to the ends of the take-up frame D , so that each roller can turn thereon freely. The woven cloth l passes over this sectional roller and out in front over the breast-beam, and the cloth is gripped onto the several sections of this roller by a series of pressure-rollers, m , one for each fluted roller j . These pressure-rollers are mounted in a series of short levers, n , one roller in each lever, and these levers are pressed down to gripe the cloth by the tension of a strip of india-rubber, o , or other spring acting on each separately and capable of being modified in tension, each independent of the other, by screws or other suitable device acting on each. The levers n of the pressure-rollers m , with their several springs o , are mounted in a frame, E , which is connected with the frame D of the take-up roller by journals p , so that the whole series can be lifted from the take-up rollers to liberate the cloth, if desired; or their gripping pressure may be increased by turning two screws, q , which pass through holes in the ends of a bar, r , of the frame E and are tapped into the take-up frame D .

Below the sectional take-up roller there is a series of ratchet-levers, s , one such lever and ratchet or pawl for each fluted roller j . These levers all vibrate on a fulcrum-rod, t , mounted in the take-up frame D , and they are so situated that when their lower arms are pushed toward the breast-beam their ratchet hands or pawls take into the flutes or ratchet-teeth of the rollers j and turn them to take up the woven cloth.

I deem it best to have two ratchet hands or pawls on each lever, and to have one slightly shorter than the other, so that they will engage the teeth on the rollers alternately, and I thus avoid the necessity of making the teeth or flutes on the rollers very fine; and I also prefer to use weighted instead of spring pawls.

Cords u extend one from each of the said levers s , pass under roller v , and are attached to the mail-cords w of the jacquard, taking care to have the cord of each lever connected with that section of the mail-cords of the jacquard which controls the corresponding section of the warps, so that when any of the warps of a section are operated by the jacquard the lever s of the corresponding section of the take-up will be drawn toward the lay until it

strikes a stop-bar, y ; and as the range of motion of the mail-cord of the jacquard is greater than the motion given to the lever, the cord which is attached to the lever has a section of india-rubber or other substance which will yield, and when the lay makes its forward beat to beat up the weft-thread a bar, x , secured to the front face of the race-beam of the lay by screws inserted through slots, so as to project forward to any desired extent, will strike the lever s , vibrate it in the opposite direction, and thus turn the fluted roller j the required distance to take up the woven cloth in a corresponding portion of its width. The bar x should be made adjustable to admit of varying the amount of take-up. In this way it will be seen that the jacquard merely sets the levers of the take-up, and that no portion of the power required to take up the cloth is borne by the jacquard, but is all derived directly from the lay. It should be observed that by the time the lay strikes the levers of the take-up the jacquard has made its return motion and liberated the cords by which the levers of the take-up were set.

The shuttle a^1 is operated by a pair of carriers, $b^1 b^1$, which slide in suitable ways in the race-beam of the lay. Both carriers are alike, and each consists of a bar fitted to slide in the ways, and having a standard at the outer end, from which an arm, c^1 , extends inward and parallel with the bar. To the arm is connected a spring-catch lever, d^1 , by a fulcrum-pin, e^1 , situated at about the middle of its length.

The shuttle, near its back edge, is formed with a groove in its under side, extending from each end to within a short distance of the middle, which grooves receive the arms c^1 of the carriers; and the upper face of the said shuttle is grooved in like manner to receive the inner end of the spring-catch levers d^1 of the carriers, each of which, at the proper time, catches over a cross-pin in the said groove to hold the shuttle on the arm. The shuttle being held on the arm c^1 by the catch-lever d^1 of one of the carriers, and both carriers being set in motion toward the center of the lay, as the two carriers approach each other the arm and spring-catch lever of the opposite carrier enter the grooves of the shuttle, and the catch-lever snaps over the cross-pin in the shuttle-groove and takes hold of the shuttle, and at the same time the tail end of the catch-lever of the carrier which carried the shuttle in is depressed by a pin, e^3 , to liberate the shuttle. In this way the first carrier is made to liberate the shuttle as the second takes hold of it, and the motion of the two carriers is then reversed to move them back to their original positions, and in doing this the shuttle is carried entirely across the warps to the other side preparatory to another operation in the reversed direction.

To guide the shuttle from one carrier to the other, and to prevent the arms and catch-levers from catching against any of the warp-threads, there is a thin plate, f^1 , attached to the back of each carrier, one of them a little far-

ther back than the other, and slightly inclining back, so that as the carriers approach they shall lap by each other, and in so doing direct the shuttle and the carriers so that the arm and catch-lever shall properly enter the grooves of the shuttle. These plates are a little wider than the thickness of the shuttle and a little longer, and pointed at the outer end, so as to spread the warp-threads and prevent the arms and catch-levers and the shuttle from catching and breaking any of the warp-threads.

As the catch-levers of the two carriers are to be opened alternately to liberate the shuttle, the pins $e^3 e^3$, for that purpose, project from two short arms, $g^1 g^1$, hinged at their upper ends to the lay, and the lower ends of both are connected by a rod, h^1 , so that they shall vibrate together; and one end of this rod is in turn connected by a link with one arm of a rock-lever, i , on the lay, and this rock-lever has two arms, i^1 and j^1 , which are alternately acted upon by two tappets, $k^1 k^1$, projecting from the back face of a tappet-wheel, l^1 , that turns on a stud-pin on the lay; and this wheel has four pins, m^1 , projecting from its front face at equal distances apart, which are acted upon in turn by a spring-catch, n^1 , hinged to one of the carriers, to turn the said wheel a quarter of a revolution every time the carriers approach each other in the middle of the lay. This causes the tappets k^1 to vibrate the double lever $i^1 j^1$, and alternately in opposite directions, and thereby place the pins $e^3 e^3$ on the arms $g^1 g^1$ in the positions required alternately to operate the catch-levers of the carriers. Above the tappet-wheel l^1 there is a lever, o^1 , drawn down by a spring, so that its face shall bear on two of the four pins, m^1 , to prevent the wheel from being turned by jars after the catch n^1 has turned it a quarter of a revolution.

The carriers are both moved inward toward the center of the loom by cams $p^1 p^1$ on the main shaft, which depress two levers, $q^1 q^1$. The outer ends of these levers are connected by a bar, r^1 , and from the middle of this bar two straps or cords extend up and pass in opposite directions, each over a roller, s^1 , mounted in hangers from the under side of the race-beam, and the ends of these cords are attached to arms $t^1 t^1$, extending down from the carriers, and which slide in slots made for that purpose in the race-beam; and to the said arms $t^1 t^1$ are attached two other straps, $u^1 u^1$, one to each, which pass over two other rollers, $v^1 v^1$, near the end of the race-beam, and extend down, and are attached to two levers, $w^1 w^1$, one on each side of the loom and outside of the frame, and these levers are depressed simultaneously and at the required time by two cams, $x^1 x^1$, one on each end of the main shaft.

The forms and relative position of the two sets of cams p^1 and x^1 are represented in Fig. 6.

For the purpose of drawing out the surplus weft-thread after each throw of the shuttle, when the interweaving is performed on less than the whole width of the cloth, there are

two thread-pullers, $a^2 a^2$, one on each side of the loom, and so located that they shall operate near to the selvage of the cloth. As both thread-pullers and their connections are alike, the description of one will answer for both. The thread-puller consists of a finger, a^2 , with the forward end curved a little downward to prevent the thread from escaping from under it. It is hinged to the upper end of a rod, b^2 , and is provided with a spring, c^2 , which holds it at the required angle to pull the thread, and the spring is of such delicate tension as to yield and liberate the thread when it has been pulled to the requisite extent. The rod b^2 is in like manner hinged to the end of a lever, d^2 , and held at the required angle by the tension of a spring, e^2 . The lever turns on a fulcrum-pin, f^2 , at the back of the loom, and is drawn upward by the tension of a spring, g^2 , and it is depressed against the tension by a cam, h^2 , on the main shaft, the form of which cam is clearly represented in Fig. 8 of the drawings.

The thread comes out of the front edge of the shuttle a^1 , and, as will be seen, when the thread-puller is elevated the point of the finger is between the front edge of the shuttle and the reed, and it gets to that elevated position before the shuttle is brought home, so that when it is depressed by the cam h^2 the finger is sure to catch the thread and pull it down until the required tension is given to it to insure that there shall be no portion of it left loosely projecting from the surface of the cloth when woven, and beyond that tension the finger will open and liberate the thread.

When the interweaving is extended entirely across the whole width of the warps, the operation of the thread-pullers must be suspended, and this is effected in the following manner: On the side of the lever d^2 there is a projecting pin, i^2 , against which a catch-lever, j^2 , catches to hold down the lever d^2 , and with it the thread-puller, in the depressed position. The catch-lever j^2 rests on the periphery of an oval cam, k^2 , on an arbor, l^2 , and from this arbor project four large ratchet-teeth, m^2 , which are acted upon to turn the cam a quarter of a revolution at a time by a spring ratchet-hand, n^2 , on one end of a lever, o^2 , the other end of which lever is connected to a cord, p^2 , attached to a needle of the jacquard. When this lever o^2 is operated by the jacquard, the cam k^2 is turned a quarter of a revolution, bringing it to the position represented in Fig. 8 of the drawings. That lifts the catch-lever j^2 to the position represented, liberates the lever d^2 , and sets the thread-puller into action, and it will continue to act until the jacquard again operates the lever o^2 , turns the cam another quarter-revolution, which permits the catch-lever j^2 to catch the lever d^2 of the thread-puller, and there hold it out of action until the next change is indicated by the jacquard.

As before stated, there is one thread-puller on each side of the loom, both constructed alike and having like appendages, and each

operated by a separate cam on the main shaft, and each is provided with a separate mechanism connected with the jacquard; and it is necessary that they should be separate, because at times one must be out of action while the other is in action.

The yielding of the arm a^2 , so as to allow the thread to slip off and escape so soon as it is sufficiently tightened, allows the arm d^2 to be operated uniformly whether there is much or little slack thread to be gathered, and avoids the necessity which might otherwise be experienced of giving a varying range to its motion suited to the varying length of slack to be gathered in weaving gores.

In this kind of weaving it is important that the reed should beat up the weft-threads very close to the sectional take-up, and this result cannot be obtained with a fly-shuttle, for the reason that the fly-shuttle must have a wide race-beam before the reed on which to travel; but by combining with a sectional take-up mechanism shuttle-carriers substantially such as herein described, a surface for the shuttle to run on is dispensed with, and the difficulty pointed out thereby avoided.

By the means above described the weaving operation can be carried on at any portion of the width of the cloth and suspended at other portions of the width, and this may be done along any desired portion of the length, so that the cloth, instead of being woven flat, as ordinary cloth is woven, can be produced with gore-like swells, which, when made into corsets, will fit the protuberances of the body, or answer any other purpose requiring such irregular weaving.

What I claim as my invention, and desire to secure by Letters Patent, is—

1. Operating the sectional take-up roller by levers which are set by the jacquard and oper-

ated to take up the woven cloth by the beat of the lay or the motion of some equivalent part of the loom, substantially as and for the purpose specified.

2. In combination with the sectional take-up roller, the series of pressure-rollers and the frame in which they are hung, with its connections, so that while each can yield independently of the others the whole of them can be lifted from the take-up roller at once or the tension of their springs increased, substantially as and for the purpose specified.

3. The thread-pullers, in combination with the jacquard and the intermediate mechanism by which the jacquard is made to determine when the said thread-pullers shall be thrown in or out of action, substantially as and for the purpose specified.

4. Connecting the finger of the thread-puller by means of a spring with the mechanism by which it is operated, so that it shall liberate the thread so soon as it shall have been pulled with sufficient tension, substantially as specified.

5. The adjustable bar on the lay, in combination with the levers that operate the sectional take-up, and the bar which gages the extent to which the said levers shall be pulled by the jacquard, substantially as and for the purpose specified.

6. The shuttle-carriers for operating the shuttle, or the equivalents thereof, as distinguished from the fly-shuttle system, in combination with the sectional take-up, or the equivalent thereof, substantially as and for the purpose described.

WM. BREITENSTEIN.
